UNITED STATES PATENT OFFICE.

SIDNEY G. HIRSCHBERG, OF NEW YORK, N. Y.

DESIGN FOR A CHILD'S HAT.

No. 39,392.

Specification for Design.

Patented June 30, 1908.

Application filed March 24, 1908. Serial No. 423,059. Term of patent 3½ years.

To all whom it may concern:

Be it known that I, SIDNEY G. HIRSCHBERG, a citizen of the United States, residing at New York city, in the county of New York and State of New York, have invented a new, original, and ornamental Design for Children's Hats, of which the following is a specification, reference being had to the accompanying drawing, forming part thereof.

The figure is a perspective view of a hat embodying my new design.

I claim:

The ornamental design for a child's hat, as shown.

SIDNEY G. HIRSCHBERG.
